United States Patent Office

Des. 218,795
Patented Sept. 29, 1970

218,795

ENCLOSED CHILD'S CRIB OR SIMILAR ARTICLE

Gloria Caranica, Monroe, Conn., assignor to Universal Education Corporation, New York, N.Y., a corporation of New York

Filed June 16, 1969, Ser. No. 17,719

Term of patent 14 years

Int. Cl. D6—01

U.S. Cl. D5—5

FIG. 1 is a front perspective view of an enclosed child's crib or similar article having the access means depicted in the open position;

FIG. 2 is a rear perspective view of the playcrib of FIG. 1;

FIG. 3 is a front elevation view of the playcrib of FIG. 1 with the access means depicted in the closed position; and

FIG. 4 is an end elevation view of the playcrib of FIG. 1.

Portions of the drawing figures have been diagonally lined to indicate transparency.

I claim:

The ornamental design for an enclosed child's crib or similar article, as shown and described.
